(57) **CLAIM**

The ornamental design for a solar key ring, as shown.

DESCRIPTION

FIG. 1 is a front view of a solar key ring showing my new design;

FIG. 2 is a back view thereof;

FIG. 3 is a side view thereof;

FIG. 4 is a side view thereof;

FIG. 5 is a bottom view thereof; and,

FIG. 6 is a top view thereof.

The broken lines showing the ring and the name are for illustrative purposes only and form no part of the claimed design.
